UNITED STATES PATENT OFFICE.

CHARLES E. SARGENT, OF INDIANAPOLIS, INDIANA.

INTERNAL-COMBUSTION ENGINE.

Application filed April 18, 1921. Serial No. 462,254.

To all whom it may concern:

Be it known that I, CHARLES E. SARGENT, a citizen of the United States, residing at 2020 Delaware Street, Indianapolis, in the 5 county of Marion and State of Indiana, have invented a new and useful Improvement in Internal-Combustion Engines, of which the following is a specification.

This invention relates to internal combustion engines and particularly of the automotive type.

The primary object of this invention is to increase the thermal efficiency of automotive engines at all loads, but particularly at light 15 loads at which automobiles are operating 90% of the time.

This invention secures the increased efficiency by providing means for expanding the working medium to practically atmospheric pressure at all loads and for decreasing the fuel content and increasing the compression as the load decreases.

Heretofore it has been customary in engines of the automotive type to operate 25 with maximum compression at full load, and to release the gases during the working stroke before the piston has reached the point where compression began, and to throttle the mixture, thereby reducing the 30 compression and efficiency, as the load becomes less.

The result of the present system or cycle is that about 40% of the heat is rejected to the exhaust at full load, and the efficiency 35 is rapidly lowered with less than full load where automobiles are normally operated as the compression becomes less and the wire-drawing and back pressure which acts as a brake, increases.

40 The Sargent cycle used in this invention, so-called to distinguish it from the Otto cycle upon which all automobile engines operate, provides for increasing the compression and decreasing the fuel as the load gets lighter 45 and conversely increasing the fuel and decreasing the compression as the load gets heavier and for expanding the working charge to practically atmospheric pressure at all loads.

50 Referring now to the drawings;

Fig. 1 is a partial side elevation of an automotive engine embodying the invention;

Fig. 2 is a partial top plan view with the 55 cover removed showing the valve operating mechanism;

Fig. 3 is a partial section on the broken line 3—3 of Fig. 2;

Fig. 4 is a partial plan view of the mechanism for operating the inlet cam shaft;

Fig. 5 is a vertical section on the line 5 60 of Fig. 4;

Fig. 6 is a vertical section through the carburetor on line 6 of Fig. 7;

Fig. 7 is a horizontal section on the line 7 of Fig. 8;

Fig. 8 is a vertical section on the line 8 65 of Fig. 7; and

Fig. 9 are indicator diagrams at full and light loads.

In the embodiment shown in Fig. 1 the 70 block 10 comprises four cylinders cast integral to which is secured a cylinder head 11 which is common to all cylinders by means of bolts 12. Inlet ports 13 are formed upon one side of the cylinder head and communicate with the cylinders 10 while exhaust ports 14 as shown in dotted lines in Fig. 3 are formed in the opposite side of the cylinder head.

Each of the inlet ports terminates in a 80 tapered seat 15 having a cylindrical seat 16 above it. These seats are covered by inlet valves 17 having corresponding tapered and cylindrical faces, the purpose of which as will later be explained is to give a quick 85 opening and closing of the valves and to prevent wire drawing of the charge. These valves slide in guides 18 in the head and are normally held on their seats by means of springs 19. Similar exhaust valves (not 90 shown) in detail are similarly mounted in the head.

The inlet valves are operated by individual bell cranks 20 hingedly mounted at 21 and having rollers 22 journalled on the 95 lower end thereof, each of which engages a cam 23 on the cam shaft 24. This cam shaft is journalled in suitable bearings in the cylinder head and is driven by suitable gearing from the engine crank shaft (not shown) 100 and at one half its speed, as this is a four cycle engine. In the same way the exhaust valves are operated by means of bell cranks 25 and cams 26 on the exhaust cam shaft 27. The inlet cam shaft 24 is movable end- 105 wise to vary the time of closing of the inlet valve which varies the compression as will later be explained.

The inlet manifold 28 connects each of the inlet passages 13 with the carburetor 29 110

which is shown in detail in Figs. 6, 7 and 8. The main mixing passage 30 has upon the inside of its outer wall a series of spiral flutings 31. The bottom of this passage 5 is closed by means of a casting 32 having a cylindrical portion 33 extending up into the passage and terminating in a cap 34. A piston 35 is slidably mounted within the cylinder 33 and carries a metering pin 36 10 which is slidable in the tube 37. This tube is integral with and carried by casting 32.

When the engine is not in operation the pin 36 serves to close the passage 39 which leads to a gravity feed fuel tank (not 15 shown). A tapered groove 40 is formed in the side of the pin 36, which is much larger at the bottom than at the top and communicates with the space at the bottom of the pin 36. An annular groove 41 is formed 20 within the tube 37 at about the height of the upper end of the groove 40 when the piston 35 is at the bottom of its travel. A series of radial passages 42 connect this groove with the vertical nozzles 43, the latter terminating in the bottom of the rectangular shaped passages 44 in the side of the cylinder 33. Openings 45 in the bottom of the casting 32 permit air to pass up 25 from the tube 38, over the nozzles 43 and in through the mixing chamber 30.

A sleeve 46 is rotatably mounted upon the sleeve 33 which has a series of openings 47 which are substantially the same size and shape as the openings 44 and adapted to 30 register therewith. A screw 48 passes through the slot 49 in the side of the carburetor casting 29 and is secured to the sleeve 46. The head of this screw contains a socket in which is pivotally mounted a rounded end of a link 50, the opposite ends of the link being similarly mounted in the 40 short arm of a bell crank 51 which is pivotally mounted at 52.

It will be understood from the foregoing 45 that as the bell crank is moved the sleeve 46 will be rotated upon the cylinder 33 thereby partially covering and uncovering the openings 44 therein.

The longer arm 53 of the bell crank is 50 connected by means of a link 54 with the lever arm 55 which is carried by a shaft 56 which is journalled in the side of the head 11 as shown in Fig. 5. The lever 55 is operably connected to the lever 57 which is 55 controlled by the operator through the rod 58. This rod may be connected either through a foot accelerator or through a hand controlled lever.

A lever 56^a is keyed on the inner end of 60 this shaft 56 and carries a pin 59 on which is journalled a roller 60 which lies between the flanges 61 on the intake cam shaft 24. Thus it will be understood that as the lever 57 is moved back and forth the inlet cam 65 shaft 24 is moved back and forth changing

the point of closing of the inlet valve and thus increasing the compression in the cylinder as the cam shaft 24 is moved to the left and decreasing the compression as the cam shaft is moved to the right. The advance face of the cam is preferably made straight and hence the time of opening in the inlet valve will remain substantially the same in all cases. Referring now to Fig. 3, it will be observed that by the use 70 of the piston extension on the poppet valve, a quick opening and closing is obtained, as the valve is moving rapidly except when close to the seat, while the final seating of the valve may take place relatively slowly. 75 Thus, a valve is provided which is quick opening and closing and at the same time is relatively noiseless.

Referring now to Figs. 6, 7 and 8, the slight rarefaction in the intake manifold 28 transmitted through the hole 34^a will cause the piston 35, as shown in Fig. 8, to rise uncovering the inner side of the openings 44. The space over the top of the piston 35 communicates with the intake manifold through 80 a small opening 34^a so that the piston 35 will not have a tendency to flutter with all the minor fluctuations of pressure in the intake manifold. As the suction increases the piston 35 will be raised uncovering a 85 greater area of the opening 44, and at the same time, raising the pin 36 so that a larger part of the groove 40 will be brought over the annular groove 41 and consequently a greater amount of fuel will be fed 90 to the nozzles 43.

As the cam shaft 24 is moved to the left to give increased compression, the sleeve 46 is simultaneously turned in a clockwise direction as shown in Fig. 7 bringing the 105 openings 47 more nearly into registration with the openings 44. The air is thus admitted more rapidly into the intake passage and the vacuum drops somewhat, causing the piston 35 to fall. The piston carries the metering pin with it thereby decreasing the area of the notch 40 in front of the groove 41 and decreasing the flow of fuel to the nozzles 43. It will thus be seen 110 that the volume of air admitted to the cylinder is increased as the inlet valve is held open longer by the large end of the cam 23 and that at the same time the amount of fuel fed is decreased. In other words, the port widens and to maintain the same equilibrium or pressure ratio between the air in the manifold and outside the manifold constant, the piston 35 will drop reducing the fuel supply though the air velocity (a constant in this form of carburetor) will 115 be the same. This velocity is approximately constant because the difference in pressure on the two sides of the opening 44 is nearly constant while the engine is running, being balanced by the constant 120

weight of the piston 35. The volume of air is controlled by the area of the openings which in turn depends upon the position of the sleeve 46 and upon the height of the 5 piston 35.

The openings 44 and 47 are placed at an angle so as to give the entire mass of fuel and air a whirling motion as it enters the chamber 30. The spiral flutings 31 are 10 formed in the side walls to increase this action. The hot air passage 63 is formed about this mixing chamber and exhaust gases are led thereto through the pipe 64, which heat the fluted walls and pass out to 15 the atmosphere through the opening 65. The centrifugal force developed throws the ungasified fuel on this hot surface where it becomes gasified and passes into the air current while the air absorbs very little heat 20 as it only touches the top of the plates.

A butterfly valve 66 is placed in the passage 25 and connected by means of a rod 67 with the bell crank 63 so that as the amount of fuel fed is decreased, the valve 66 will be closed, thereby decreasing the flow of 30 exhaust gases to the heating chamber 63.

If we turn now to the indicator diagram as shown in Fig. 9 and assume that the piston is at the top of its stroke which corresponds to the position A on the diagram, 35 and that the cam shaft is set for extreme no-load position, the line A B will represent the suction stroke, the line B C will represent the compression stroke, the line C D will represent the rise in pressure due to 40 ignition, the line D B is the working stroke and B A which is substantially the same as the line A B is the exhaust stroke.

If, however, on the intake stroke we cut 45 off at two thirds stroke the intake line will then be A E F, F G will be the compression line, G H the rise due to ignition, H B the expansion line and B A the exhaust line as before.

Instead of closing the admission valve and cutting off at approximately two thirds the 50 suction stroke at full load, substantially the same result may be obtained by permitting the inlet valve to remain open during approximately one third of the compression stroke. In that case the inlet valve would close at E on the return or compression stroke instead of at E on the outward or suction stroke as before. The compression line E G, the ignition line G H and the 55 expansion line H B would remain substantially the same as before. In a multiple cylinder engine the charge forced out of one cylinder for this $\frac{1}{3}$ stroke is drawn into another so that there is very little regurgitation through the carburetor.

In order to increase the compression for 60 light loads when closing the admission valve at approximately one third the compression stroke, the inlet cam must be so beveled that

when moved for light loads the closing of the admission valve will be earlier, while in the first method described the admission valves would be closed later. In both cases, the nearer the admission valve closes to the 70 end of the stroke, the higher will be the compression.

Either of these methods provides for complete combustion and complete expansion at all loads with a consequent lowering of the 75 heat of the exhaust and a great decrease in the noise of the exhaust.

While I have shown and described but two embodiments of my invention, it is to be understood that it is capable of many 80 more modifications. Changes, therefore, in the construction and arrangement may be made without departing from the spirit and scope of the invention as disclosed in the appended claims, in which it is my intention 85 to claim all novelty inherent in my invention as broadly as possible in view of the prior art.

What I claim as new and desire to secure by Letters Patent is:

1. In an internal combustion engine, a cylinder, a piston therein, an inlet valve and an exhaust valve in said cylinder, means for varying the time said inlet valve is open whereby the compression in said cylinder 95 is varied, a carburetor and means operably connected to said first-mentioned means for decreasing the fuel content of the mixture as the compression is increased and for increasing the fuel content of the mixture as 100 the compression is decreased.

2. In an internal combustion engine, a cylinder, a piston therein, an inlet valve and an exhaust valve in said cylinder, a cam shaft having a cam for operating said inlet 105 valve, said cam having a longitudinally varying face and means for shifting said cam shaft longitudinally for varying the time of closing said inlet valve whereby the compression in said cylinder is varied, a carburetor and means operably connected to said first mentioned means for decreasing the fuel content of the mixture as the compression is increased and for increasing the fuel content of the mixture as the compression is decreased.

3. In an internal combustion engine, a cylinder, a piston therein, an inlet valve and an exhaust valve in said cylinder, a cam shaft having a cam for operating said inlet 120 valve, said cam having a longitudinally varying face and means for shifting said cam shaft longitudinally for varying the time said inlet valve is open whereby the compression in said cylinder is varied, a carburetor having an opening for the passage of air, a fuel nozzle adjacent said opening, and means operably connected to said first-mentioned means for varying said opening for decreasing the fuel content of the 125

mixture as the compression is increased and for increasing the fuel content of the mixture as the compression is decreased.

4. In an internal combustion engine, a cylinder, a piston therein, an inlet valve and an exhaust valve in said cylinder, a cam shaft having a cam for operating said inlet valve, said cam having a longitudinally varying face and means for shifting said cam shaft longitudinally for varying the time of closing of said inlet valve whereby the initial pressure in said cylinder is varied, a carbureter having an opening for the passage of air, a fuel nozzle adjacent said opening, and means operably connected to said first mentioned means for varying said opening for decreasing the fuel content of the mixture as the compression is increased and for increasing the fuel content of the mixture as the compression is decreased.
5. In an internal combustion engine, a cylinder, a piston therein, an inlet valve and an exhaust valve in said cylinder, means for varying the time the inlet valve is open whereby the compression in said cylinder is varied, a carbureter having a plurality of openings for the passage of air, a fuel nozzle adjacent said openings, and means operably connected to said first-mentioned means for varying said openings for decreasing the fuel content of the mixture as the compression is increased and for increasing the fuel content of the mixture as the compression is decreased.
- 10 cam shaft longitudinally for varying the time of closing of said inlet valve whereby the initial pressure in said cylinder is varied, a carbureter having an opening for the passage of air, a fuel nozzle adjacent said opening, and means operably connected to said first mentioned means for varying said opening for decreasing the fuel content of the mixture as the compression is increased and for increasing the fuel content of the mixture as the compression is decreased.
- 15
- 20
- 25
- 30

ing the fuel content of the mixture as the compression is decreased.

6. In an internal combustion engine, a cylinder, a piston therein, an inlet valve and an exhaust valve in said cylinder, means for varying the time of closing of said inlet valve whereby the compression in said cylinder is varied, a carbureter having a plurality of radial openings for the passage of air, a fuel nozzle adjacent said openings, and means operably connected to said first-mentioned means for varying said openings for decreasing the fuel content of the mixture as the compression is increased and for increasing the fuel content of the mixture as the compression is decreased.

7. In an internal combustion engine, a cylinder, a piston therein, an inlet valve and an exhaust valve in said cylinder, means for varying the time said inlet valve is open whereby the compression in said cylinder is varied, a carbureter having a mixing chamber, a plurality of radial openings for the passage of air into said mixing chamber, a fuel nozzle adjacent said openings, means operably connected to said first-mentioned means for varying said openings for decreasing the fuel content of the mixture as the compression is increased and for increasing the fuel content of the mixture as the compression is decreased and means for heating the walls of the mixing chamber.

CHARLES E. SARGENT.
